UNITED STATES PATENT OFFICE

EDWIN E. ARNOLD, OF PITTSBURGH, PENNSYLVANIA, ASSIGNOR TO WESTINGHOUSE ELECTRIC & MANUFACTURING COMPANY, A CORPORATION OF PENNSYLVANIA

MEANS FOR JOINING SHEET MATERIAL

Application filed November 21, 1929. Serial No. 408,913.

My invention relates to the art of joining and fastening sheets of material and has particular relation to a means for joining non-metallic sheet material such as molded phenolic condensation products, or the like, or fastening the sheets to other objects. It is well known in the art of joining sheets of material that the rivet holes weaken the structure and that no matter how the rivets and rivet holes are located, the full efficiency of the sheet in tension cannot be secured.

In addition, where the ordinary and known methods of riveting are applied to sheet material such as molding laminated material, difficulties are encountered and, therefore, I have devised a means for joining and fastening sheet material which obviates the difficulties of the prior art.

An object of my invention, therefore, is to furnish a means for joining and fastening sheet material such that the full efficiency of the sheet may be maintained at the joint.

Another object of my invention is to provide a means for re-enforcing predetermined portions of sheets of laminated material.

Other objects of my invention will become apparent from the following description of my fastening means taken in connection with the drawings.

Referring to the drawings:

Figure 1 is a top plan view of a sheet of material with my re-enforcing means disposed in the sheet. A portion of one covering layer has been drawn back in order to expose the re-enforcing means.

Figure 2 is an end view of the sheet shown in Fig. 1.

Fig. 3 is a top plan view of a joint between two molded sheets made according to one modification of my invention.

Fig. 4 is an end view of the sheets shown in Fig. 3.

Fig. 5 is a top plan view of sheets of material joined in accordance with other embodiments of my invention, and

Fig. 6 is an end view of the sheets shown in Fig. 5.

With particular reference to Fig. 1, my re-enforcing means is preferably comprised of interlaced iron or steel wire 1 or the like. The

wire may be of a resilient material such as resilient iron or steel wire in order that the re-enforced sheet will retain its formed shape, or may be a malleable material such as soft iron wire which will assist in maintaining the sheet in any flat or curved shape given it after molding. If desired, the re-enforcing means may be a nonmetallic structure such as heavy cords of fibrous material.

The re-enforcing means is particularly well adapted for use with molded laminated material and may be inserted between sheets 2 and 3 along the edge of the sheet material as shown in Fig. 1 or disposed in strips or patches wherever it is desirable to re-enforce the sheet material. When the sheet material is re-enforced and strengthened in this manner, obviously its tensile strength is greatly increased and, therefore, when sheets of material having my re-enforcing means disposed therein are over-lapped and riveted, as for instance, by means of a row of rivets 11 (Figs. 5 and 6), the strength of the joint is as great as or greater than the tensile strength of the sheet material in its normal condition.

If the sheet material is to be fastened to other objects they are locally re-enforced at the point where they are to be fastened and may then be secured to the object in any desired manner, as for instance by nails or screws and the sheet at the point will be as strong or stronger than the sheet without re-enforcement.

Another means of joining or fastening the sheets of material is provided by punching a series of openings 12 through the over-lapping sheets and stitching a binding material 13, such as wire, fibrous material, or the like, through the holes in any of the well known methods. The drilling of the holes and stitching of the binding material may be accomplished in separate operations or may be accomplished in one operation, such as the ordinary operation of sewing.

Another method of securing sheets of material re-enforced by my re-enforcing means is shown in Fig. 3. In this method of securing, the sheets 21 and 22 are bent back over one another so that a double over-lapped or hooked joint 23 is secured and the joint may

be fastened by riveting or sewing in the manner hereto described. In this case, the reinforcing utilized preferably should be soft metal wire adapted to be easily bent back upon itself in the manner shown.

5 My joining means is particularly well adapted for joining the sheets of molded material which are to be utilized in cases where long continuous sheets are desirable, such as for instance, in covering the wings of aeroplanes or for use as covering material in lighter-than-air aeronautical vehicles.

10 The locally re-enforced sheets may be utilized whenever it is desirable to fasten the sheets to other objects, such as the fuselage or frame of an aeronautical vehicle or when it is desirable to fasten objects to the sheets or in fact in any case where openings must be made in the sheet which would ordinarily 15 make the sheet adjacent the opening weaker than the surrounding sheets.

15 Although I have described specific embodiments of my invention, it is apparent that modifications may be made by those skilled 20 in the art. These modifications may be made without departing from the spirit and scope of my invention as set forth in the appended claims.

I claim as my invention:

30 1. An article of manufacture comprising a sheet of laminated material composed of layers of fibrous material bound together with a heat-hardened binder, said sheet having a reinforcing means molded in the margin of one or more of its edges, the remainder of the sheet being unreinforced, said reinforcing material serving as a strengthening material so that, when the material is joined to another object by mechanical means, the 35 strength of the joint produced will be at least as great as the unreinforced sheet material in its normal condition.

2. An article of manufacture comprising a plurality of sheets of laminated material 40 composed of layers of fibrous material bound together with a heat-hardened binder, each sheet of laminated material having reinforcing means extending a short distance into its margin, the remainder of the sheets being unreinforced, and mechanical fastening means for uniting said sheets together at the reinforced edges, said reinforcing means at the edge portions to be joined serving as a strengthening means so that the joint formed 45 will have a mechanical strength at least as great as the unreinforced sheet material in its normal condition.

3. An article of manufacture comprising a plurality of sheets of laminated material 50 composed of layers of fibrous material bound together with a heat-hardened binder, said sheets having a wire reinforcing material extending a short distance into their margins, the remainder of the material being unreinforced, and mechanical means for unit-

50 ing the sheets together at the reinforced edges, the reinforcing means at the margins of the sheets serving to impart sufficient strength to the laminated material at the joint to compensate for the weakening caused by the mechanical uniting of the material so that the joint produced by uniting of the sheets will be at least as strong as the unreinforced sheet material in its normal condition.

55 4. An article of manufacture comprising a plurality of sheets of laminated material composed of layers of fibrous material bound together with a heat-hardened binder, each of said sheets having reinforcing means extending a short distance into the margin of one or more of its edges, the remainder of said sheets being unreinforced, and means for fastening two or more of said sheets together at the reinforced edges, said means including a joint in which the margins of the sheets containing the reinforcing material are in overlapping relationship with respect to each other and mechanical means passing through the overlapping structure.

60 5. An article of manufacture comprising a plurality of sheets of laminated material composed of layers of fibrous material bound together with a heat-hardened binder, each of said sheets of laminated material having wire reinforcing means extending a short distance into the margin of one or more of its edges, the remainder of said sheets being unreinforced, and means for fastening two or more of said sheets together at the reinforced edges, said means including a joint in which the margins of the sheets containing the reinforcing material are in hooked, overlapping relationship with respect to each other, and mechanical fastening means passing through the hooked overlapping structure.

65 In testimony whereof, I have hereunto subscribed my name this 18th day of November, 1929.

EDWIN E. ARNOLD.
